UNITED STATES PATENT OFFICE

2,104,963

ELECTRIC DOOR CHIME

Edwin G. Anderson, San Diego, Calif.

Application May 31, 1934, Serial No. 728,366

3 Claims. (Cl. 116—149)

My invention relates to electric door chime, and the objects of my invention are:

First, to provide an electric door chime in which each of a series of chime tubes is struck in a predetermined sequential order upon pressing a push button;

Second, to provide an electric door chime which upon being set into operation continues to the completion of its cycle even though the 10 circuit to the push button is broken;

Third, to provide an electric door chime in which the sequential arrangement of the tone obtained may be varied;

Fourth, to provide an electric door chime 15 which incorporates a novel clapper means which is so arranged that each chime tube is struck only once when the clapper is released, and

Fifth, to provide on the whole a novelly constructed electric door chime which is durable, 20 efficient in its action, and which will not readily deteriorate or get out of order.

With these and other objects in view as will appear hereinafter, my invention consists of certain novel features of construction, combination and arrangement of parts and portions 25 as will be hereinafter described in detail and particularly set forth in the appended claims, reference being had to the accompanying drawing and to the characters of reference thereon 30 which form a part of this application, in which:

Figure 1 is a front elevational view of the electric door chime with the cover member shown in section and the chime tubes shown fragmentarily and other portions of the mechanism broken away to facilitate the illustration; Fig. 2 is an enlarged longitudinal sectional view thereof through 2—2 of Fig. 1 with parts and portions shown in elevation; Fig. 3 is a transverse sectional view thereof through 3—3 of Fig. 1 40 on the same scale therewith, and with parts and portions shown in elevation, and Fig. 4 is an enlarged fragmentary sectional view through 4—4 of Fig. 1 with parts and portions shown in elevation and illustrating particularly the switch 45 means for maintaining the operation of the door chimes.

Similar characters of reference refer to similar parts and portions throughout the several views of the drawing.

50 Casing 1, frame 2, cam shaft 3, cam members 4, worm gear 5, counter shaft 6, worm 7, pulley means 8, motor 9, switch cam 10, switch means 11, supporting hooks 12, chime tubes 13, posts 14, leaf springs 15 and 16, spacers 17, cushion 55 18, striker 19, and adjustment bracket 20, con-

stitute the principal parts and portions of my novel electric door chimes.

The casing 1 comprises a base plate 1a and a suitable cover to fit thereover and define a substantially rectangular area to enclose the necessary mechanism, said casing of course is ornamented if the door chime is positioned in view. The base plate 1a supports a frame 2 which extends transversely. The frame 2 comprises a cross portion 2a having bracket portions 2b at 10 its extremities secured to the margins of the base plate. Said frame journals between the bracket portions 2b a cam shaft 3 upon which is mounted a series of cam members 4 which will be described in more detail hereinafter. 15

At approximately its central portion the cam shaft 3 is provided with a worm gear 5 which is engaged by a worm 7 mounted on a counter shaft 6. Said counter shaft is supported by one extremity from an upward extension 2c of the 20 frame 2. This extension also supports a suitable pulley means 8 operated by a motor 9.

The cam shaft 3 also supports a switch cam 10 which is in the form of a circular disc with a notch 10a therein, as shown best in Fig. 4. 25 The cam 10 operates a switch means 11. Said switch means comprises a suitably insulated base portion 11a from which extend a pair of leaf springs 11b. Said leaf springs are provided with suitable contact elements 11c which are normally separated. One of the leaf springs is provided with an insulated cam rider portion 11d which engages the cam 10 in such a manner that when the rider portion fits in the notch 10a the contact elements 11c are separated, but when 35 the rider engages the normal periphery of the cam said contact elements are engaged.

The cam members 4 are arranged in equally spaced relation along the cam shaft 3 and opposite the cam members the cross portion 2a of 40 the frame is perforated to receive supporting hooks 12. Each hook 12 supports a chime tube 13. Each chime tube is provided with a metal plug 13a in its upper end in which is secured a loop member 13b which is adapted to be suspended 45 from the corresponding hook 12.

Each chime tube is spaced forwardly of the base plate 1a and at the lower end of the base plate under each chime tube is a post 14. Each post 14 supports a pair of upwardly extending 50 leaf springs 15 and 16 which are arranged in substantially parallel relation with each other and are separated by spacers 17, one at the corresponding post 14 and one at the extremities of the leaf springs. The leaf springs are also 55

spaced apart intermediate their ends by a cushion 18 formed of rubber or the like. The leaf spring 16 which is adjacent the chime tube is provided with a striker 19. Said striker is secured with the extended spacer 17 to the two springs. Said striker comprises a relatively heavy base portion 19a in which is provided a socket adapted to receive a striker pad 19b formed of leather or the like. The leaf spring 15 projects slightly beyond the leaf spring 16 and is provided with an extremity 18a which is turned in a direction away from the chime tube and is positioned so as to be engaged by the corresponding cam member 4. Each cam member 4 is provided with one or more cam fingers 4a, as shown best in Fig. 2. The cam members rotate in a direction to force the leaf springs away from the chime tubes and thereupon suddenly release the springs so that the striker 19 engages the chime tube. Each leaf spring tends to snub the action of the other so that upon striking the chime tube the next reciprocation of the two springs is very much damped and the magnitude of their movement is insufficient to engage the chime tube again. In order to obtain the proper reciprocation or vibration of the springs, an adjustment bracket 20 is provided including a base portion 20a with an extended spring engaging end 20b, which is offset relatively to the inner side of the base portion 20a, which bracket is supported from the extremity of each post 14 in such a manner that the offset end 20b bears against the leaf spring 16 and the tension of the end 20b against the spring is dependent upon the tightness of the nut 14a on the post 14. For instance, if the nut 14a is set tightly, the end 20b will cause great tension against the spring 16. However, if this nut 14a is loosened slightly, it permits the member 20 to tilt slightly and reduces the tension on the spring. Thus it will be seen that by varying the pressure of the nut against the bracket 20, the pressure of the bracket 20 at the end 20b will be varied against the spring 16 and the proper adjustment obtained. Once said adjustment is obtained no further change in the arrangement need be made as the adjustment is permanent.

When a push button or other suitable switch is depressed momentarily, a circuit through the motor 9 is completed which causes the cam shaft 3 to turn closing the switch 11. The switch 11 is of course arranged in parallel with the push button used to initiate the operation and consequently the circuit through the motor is maintained until the cam shaft has made one complete revolution. To make this revolution the several cam members 4 release the corresponding strikers 19 in the desired sequential order.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a door chime, a vertically disposed chime element, a clapper means for said chime element including a dual leaf spring means arranged longitudinally with said chime element and having a fixed end opposite an intermediate portion of said chime element and a free end adjacent the extremity thereof, a rigid spacer between the free portion of the dual spring means, a yieldable spacer intermediate the ends of said dual spring means, a rigid spacer between the fixed end thereof, and a striker at the free end of the spring means engageable with the upper end of the chime element.

2. In a door chime, a vertically disposed chime element, a clapper means for said chime element including a dual leaf spring means arranged longitudinally with said chime element and having a fixed end opposite an intermediate portion of said chime element and a free end adjacent the extremity thereof, a rigid spacer between the free portion of the dual spring means, a yieldable spacer intermediate the ends of said dual spring means, a rigid spacer between the fixed end thereof, a striker at the free end of the spring means engageable with the upper end of the chime element, and an adjustable retarding member engaging one of the spring means of said dual spring means a slight distance from its fixed end.

3. In a door chime, a vertically disposed chime element, a clapper means for said chime element including a dual leaf spring means arranged longitudinally with said chime element and having a fixed end opposite an intermediate portion of said chime element and a free end adjacent the extremity thereof, a rigid spacer between the free portion of the dual spring means, a yieldable spacer intermediate the ends of said dual spring means, a rigid spacer between the fixed end thereof, a striker at the free end of the spring means engageable with the upper end of the chime element, one of said dual spring means being provided with an angular extended portion, and a cam engageable with said angular extended portion arranged to release said angular extended portion when said cam reaches the extremity of said angular extended portion.

EDWIN G. ANDERSON.
